UNITED STATES PATENT OFFICE.

EUGENIA MOORE, OF MILWAUKEE, WISCONSIN.

DESIGN FOR A DOLL.

Application filed January 27, 1922. Serial No. 403. Term of patent 3½ years.

To all whom it may concern:

Be it known that I, EUGENIA MOORE, a citizen of the United States, residing at Milwaukee, in the county of Milwaukee and State of Wisconsin, have invented a new, original, and ornamental Design for a Doll, of which the following is a specification, reference being had to the accompanying drawing, forming part thereof.

The drawing is a front elevational view of the doll constituting my design.

I claim:

The ornamental design for a doll, as shown.

In testimony that I claim the foregoing I have hereunto set my hand at Milwaukee, in the county of Milwaukee and State of Wisconsin.

EUGENIA MOORE.
